COSMETIC KIT

Violet Cantrell Lindstrom, 1641 Ruthlor Road, Cardiff by the Sea, Calif.

Filed Apr. 1, 1964, Ser. No. 79,292

Term of patent 14 years

(Cl. D86—10)

FIG. 1 is a top plan view of the cosmetic kit, showing all of the flaps in closed position:

FIG. 2 is a top plan view of the cosmetic kit, showing all of the flaps in open position; and

FIG. 3 is a perspective view of the cosmetic kit showing the position it assumes when it is hung, with the two side flaps and the bottom flap in open position.

The side of the cosmetic kit opposite that shown in FIG. 2 is substantially plain and unornamented.

The dominant features of my design reside in the portion shown in full lines in the drawing.

I claim:

The ornamental design for a cosmetic kit, as shown and described.
